UNITED STATES PATENT OFFICE.

FRANCIS H. CAWLEY, OF VANCOUVER, CANADA.

CALIPERS OR DIVIDERS.

SPECIFICATION forming part of Letters Patent No. 760,956, dated May 24, 1904.

Application filed March 19, 1904. Serial No. 198,999. (No model.)

To all whom it may concern:

Be it known that I, FRANCIS H. CAWLEY, a subject of the King of Great Britain, and a resident of Vancouver, in the Province of British Columbia and Dominion of Canada, have made certain new and useful Improvements in Calipers or Dividers, of which the following is a specification.

My invention is an improvement in calipers, dividers, and the like—such, for instance, as compasses; and it consists in the novel construction and combinations of parts whereby the legs are supported and may be adjusted and secured in any desired adjustment, as will be more fully described.

In the drawings, Figure 1 is a side elevation, and Fig. 2 is an edge view, of an instrument embodying my invention. Fig. 3 is a sectional elevation, the face-plate being removed. Fig. 4 is a cross-section on about line 4-4 of Fig. 3. Fig. 5 is a longitudinal section on about line 5-5 of Fig. 3. Fig. 6 is a detail perspective view of the inner side of one of the braces. Fig. 7 is a detail perspective view of the back plate. Fig. 8 is a detail view of the worm. Fig. 9 is a detail perspective view of the face-plate, and Fig. 10 is a detail perspective view of the outer side of one of the braces.

In the accompanying drawings I have illustrated my invention as embodied in a pair of compasses; but it will be understood that the invention is applicable to other implements of this class, such as calipers and dividers.

The legs A are provided with the worm-segments A', which are meshed by the worm B, the segments being journaled and the worm being journaled in a frame which comprises the back plate C, the face-plate D, and the braces E. As shown, the back plate C is provided at its upper edge with the inwardly-projecting rib C', grooved at the center at C² to coöperate with the corresponding groove D² in the rib D' of the face-plate D in forming a bearing for the worm B, a bearing for the worm-shaft on the opposite side of the worm B from the bearing C² D² being provided in a block C³, projecting forwardly from the lower edge of the back plate and having the open-

ing C⁴, in which the worm B journals at b, as will be understood from the drawings. This block C³ is also provided with the forwardly-projecting threaded stud C⁵, which receives the thumb-nut presently described. As shown, the block C³ is shouldered at C⁶ to form a seat against which rests the slotted end d of the face-plate, as will be more fully described hereinafter. This face-plate D is also provided at d' near its lower end with a groove which bears against the worm-shaft at b and aids in the operation of binding the said worm-shaft in order to lock the parts in any desired adjustment. Thus when the parts C and D are fitted together, as shown in Figs. 1, 2, 4, and 5, the worm-shaft, having at its upper end the handle B', is journaled at b' in the grooves C² and D² and at b in the opening C⁴ and groove d', the plates C and D being secured together in the manner more fully described hereinafter. The legs A have their worm-segments A' pivoted at A², the said segments A' meshing with the worm B, as shown in Figs. 3 and 4. It is preferred to support the segments so they may be adjusted toward the worm in order to hold them securely in mesh therewith, and to this end I form the back plate C and the face-plate D with laterally-elongated slots F (see Figs. 7 and 9) and provide the braces E, which comprise plates E' and a connecting-screw E² and have at E³ openings forming bearings for the screws on which the segments turn. These plates E' are provided on their inner sides with guide projections E⁴, (see Fig. 6,) which guide projections fit in the slots F and guide the lateral movements of the plates E as the latter are drawn together by the manipulation of their screws E² in adjusting the segments to properly mesh with the worm. By this means I am not only able to secure a proper adjustment of the parts to mesh as desired, but I am also able to take up wear and lost motion and secure the parts tightly in connection from time to time, as may be desired. At their upper ends the back plate and the face-plate are provided with openings for the screws G, by which they may be held together, and at their lower ends the said plates C and D are

connected by the screw-stud C⁵ and the thumb-nut H, turning thereon. It will be noticed from Fig. 5 that if the thumb-nut H be turned tightly down on the screw C it will press the 5 face-plate D at d² tightly against the worm-shaft, drawing at the same time the block C³ upwardly in the reverse direction, so that the worm-shaft will be clamped between the face-plate and back plate in such manner as to prevent 10 the same from turning. This construction also not only binds upon the worm-shaft to prevent the turning of same, but by pressing the face-plate and back plate tightly together and upon the worm-segments operates 15 to lock the said segments from moving, so that I not only secure the legs from displacement by locking the worm-shaft, but I also directly lock the worm-segments, thus preventing any accidental movement of the legs 20 A after they have been set to any desired adjustment.

At its lower end, or end opposite the handle B', the shaft of the worm B is threaded at B² and projects below the block C³ and receives 25 the nut I, by which the worm-shaft will be held firmly in its bearings in the frame of the instrument. As best shown in Fig. 9, the face-plate D is recessed on its inner side at d², adjacent to the slot d, to receive the block C³, 30 as will be understood from Figs. 7, 9, and 5 of the drawings.

The construction is simple, easily operated, and efficiently serves the purpose for which it is designed.

35 Having thus described my invention, what I claim as new, and desire to secure by Letters Patent, is—

1. The improved instrument herein described comprising the legs having worm-segments, the framing having a back plate and a face-plate provided with bearings for a worm-shaft and with laterally-elongated slots, the worm-shaft journaled between said plates and having a worm in line with the slots therein 45 and meshed with the segments of the legs, the braces comprising plates to which the segments are journaled, said plates being provided on their inner faces with guide portions movable in the slots of the frame-plates, 50 screws connecting the opposite plates of each brace whereby said plates may be drawn together, the stud projecting forwardly from the lower end of the back plate, the face-plate having an opening through which said stud 55 passes and the nut turning on said stud and adapted in coöperation therewith to bind the worm-shaft between the face and back plates and to clamp said plates upon the segments all substantially as and for the purposes set 60 forth.

2. An instrument of the class described having a framing composed of a face-plate and a back plate having bearings for a worm-shaft, a worm-shaft journaled in said bearings, the

segments journaled between such plates, the 65 worm being meshed with said segments and means for pressing the plates together whereby they may be caused to bind upon the worm-shaft and also clamp the segments substantially as and for the purposes set forth. 70

3. An instrument of the class described comprising a frame having opposite side plates, a worm journaled in the frame, the segments meshing with the worm and arranged between the opposite side plates of the frame and 75 means connecting the segments whereby they may be drawn toward each other and means for pressing the opposite side plates toward each other in the direction of the axes of the segments whereby to clamp the latter substantially as set forth. 80

4. The combination of the framing, the worm-shaft, the segments meshing with the worm of the shaft and braces comprising plates to which the segments are journaled 85 and adjusting means connecting said plates whereby the segments may be drawn together substantially as set forth.

5. The combination of the frame-plates, the worm, the brace-plates slidable along the frame-plates, means for adjusting the brace-plates toward each other and the segments journaled in connection with the brace-plates 90 substantially as set forth.

6. The combination of the legs having the 95 segments, the worm meshed with the segments, and a frame provided with means for binding the worm-shaft and for clamping the segments in the direction of the axes of the latter whereby the legs may be locked by the locking of 100 the operating-worm and by the clamping of the segments substantially as set forth.

7. The combination of the frame-plates having bearings for the worm and provided with laterally-elongated slots, the segments, the 105 worm meshing with said segments, plates having portions operating in the slots of the frame-plates and also provided with bearings for the segments and means connecting said plates whereby they may be adjusted toward each 110 other substantially as set forth.

8. The combination of the legs having segments, the worm meshing with said segments, the frame-plate provided at its lower end with a projecting block having a bearing for the 115 worm-shaft and provided with a projecting stud, the opposite frame-plate slotted at its lower end for the passage of said threaded stud, a nut on said stud for pressing the frame-plates toward each other at their lower ends, 120 means connecting such plates at their upper ends and devices carried by said frame-plates for supporting the segments substantially as set forth.

9. The combination in an instrument of the 125 class described of the frame having opposite plates provided with the laterally-elongated slots and with bearings for a worm-shaft, a

worm having its shaft journaled in said frame, segments within the frame between its plates and meshing with the worm, the braces having plates to which the segments are journaled, 5 said plates being provided with portions projecting into the slots of the framing and means for pressing the frame- plates toward each

other to clamp the segments substantially as set forth.
